UNITED STATES PATENT OFFICE.

CHARLES FREDERICK BLAKESLEE, OF FARMINGTON, ILLINOIS.

TELLURIAN.

SPECIFICATION forming part of Letters Patent No. 787,720, dated April 18, 1905.

Application filed August 1, 1903. Serial No. 167,837.

To all whom it may concern:

Be it known that I, CHARLES FREDERICK BLAKESLEE, a citizen of the United States, and a resident of Farmington, in the county 5 of Fulton and State of Illinois, have invented a new and Improved Tellurian, of which the following is a full, clear, and exact description.

The object of the invention is to provide a new and improved tellurian which is simple 10 and durable in construction, more especially designed for use in schools, lecture-rooms, and the like, and arranged to permit convenient illustration of the exact position of the earth with reference to the sun at any time of 15 the year and to demonstrate the cause of the change in seasons, the ordinary years relative to the leap-years, and various other matters of interest.

The invention consists of novel features and 20 parts and combinations of the same, as will be more fully described hereinafter and then pointed out in the claims.

A practical embodiment of the invention is represented in the accompanying drawings, 25 forming a part of this specification, in which similar characters of reference indicate corresponding parts in all the views.

Figure 1 is a front elevation of the improvement. Fig. 2 is a sectional plan view of the 30 same on the line 2 2 of Fig. 1. Fig. 3 is an enlarged sectional side elevation of the guideway, the carriage, and the support for the globe, the section being on the line 3 3 of Fig. 4. Fig. 4 is an inverted plan view of the 35 same, and Fig. 5 is an enlarged view of part of the graduated web.

On a suitably-constructed frame A is fixed an elliptical guideway B, representing the orbit or path of the earth around the sun, and 40 on the said guideway B is mounted to travel a carriage C, supporting a gravity-support D, in which is journaled the axis E' of a globe E, the said axis standing at an angle to the axis of the guideway, and in the axis of the 45 guideway is arranged a forwardly-projecting rod F', carrying the representation F of the sun, located in a vertical plane parallel to the guideway B and extending through the center of the globe E—that is, the sun is represented in the plane of the earth's orbit.

The guideway B is provided with an inwardly-extending web B', the front face of which is divided into sections G, representing the months of the year, and each section is provided with a graduation G', representing 55 the days in the month, and one day of each month has a subdivision G², representing quarter-days, and in the section for the month of December is arranged a graduation G³ at the twenty-first day, indicating the shortest day 60 of the year, and a similar graduation G⁴ is arranged at the twenty-first day in the section for the month of June, and like graduations G⁵ and G⁶ are arranged in the sections representing 65 the months of March and September at the twenty-first and twenty-second days, respectively. On the graduations G', G², G³, G⁴, G⁵, and G⁶ indicate a pointer H, held on the carriage C, so that when the carriage is caused to travel around on the guideway B the pointer H 70 indicates the corresponding day of the year at which the observation is taken to show the position of the globe E on this day relative to the representation of the sun F.

In order to hold the carriage C in any position to which it is moved by the operator, a friction device is provided, preferably in the shape of a spring-tongue C', (see Figs. 3 and 4,) formed on and secured to the carriage C and pressing on the peripheral face of the 80 guideway B.

The support D, previously mentioned, consists, essentially, of a shaft D', extending transversely and journaled in suitable bearings on the carriage C, and the rear end of the said 85 shaft D' is provided with a weight D² for holding the support D and its globe E at all times in a proper position no matter to what point the carriage C is moved along the guideway B. The front end of the shaft D' is provided 90 with an angular arm D³, having a bearing for the rear end of the axis E' of the globe E, and from this front end of the shaft D' also extends a curved arm D⁴, carrying a bearing for the outer end of the axis E' of the globe E. 95 Now by the arrangement described the weight D² on the shaft D' turns the shaft in its bearings when the carriage C is moved around on the guideway B to cause the axis E' of the globe E to stand in proper relation to the axis 100

of the guideway no matter at what day of the year the carriage is stopped along the guideway B.

- Now from the foregoing it will be seen that 5 the demonstrator with the aid of this tellurian can readily demonstrate the cause for the changes of the seasons, the exact position of the earth relative to the sun at any given time of the year, and also how the rays of the sun 10 fall upon the earth and why the north pole is in darkness while the south pole is in sun-shine, and vice versa. The demonstrator can further bring out clearly how the sun shines at both poles at the same time during the equinoxes, also why the days and nights are of equal length about the 21st of March and the 22d of September, and why the days are long and the nights are short in summer and reversed in winter.
- 20 In using the device it is advisable for the demonstrator to face south, with the tellurian in front, the globe and sun on the side nearest to him, to enable easy explanation of why the sun rises not directly east, but to the left of 25 east, and sets not directly west, but to the right of west in summer, and rises to the right of east and sets to the left of west in winter, why the sun shines straight down upon one's head at the equator on the 21st of March and 30 22d of September at noon, and why it does not at all times of the year, although the days and nights at the equator are at all times of equal length.

- In ordinary years of three hundred and 35 sixty-five days the earth does not make the complete revolution around the sun, but at the end of the three hundred and sixty-five days is one-fourth of a day behind where it was three hundred and sixty-five days before.
- 40 The web B' is supposed to represent the path of the earth around the sun and is divided into three hundred and sixty-five and one-fourth parts, representing days. The marks or graduations G² on the web represent the 45 ending of one month or the beginning of the next—that is, the lines or marks represent midnight between the two months. The spaces between the lines G² each represents one-fourth of a day—that is to say, each group of 50 the four marks G² forms three spaces, each of which represents one-fourth of a day. As the earth at the end of three hundred and sixty-five days is not in the same position in its path that it was three hundred and sixty-five days before, but is one-fourth of a day behind this position, it is evident that the 55 points in the path of the earth at which the several months begin in ordinary years of three hundred and sixty-five days vary for the 60 same month in different years. This is true not only of the first day of each month, but of all the other days of such month. The drawings show the short marks on the web, which divide the entire year into parts representing days arranged in their proper places

for leap-year. The group of marks G² represent the changes in the position of the earth, or, in other words, the different points at which the months end or begin in the several years. These marks, which divide the day into quarters, are shown only in connection with the first or last days of each month; but it is to be understood that the whole web may be divided into quarter-days, if found desirable. It must be borne in mind that each 75 of the marks in the groups G² represents the beginning of a day, or a midnight hour, and that wherever it may be the entire day lies before it. As shown in the drawings, the marks G² are of different lengths, the marks 80 of the same length in the several groups being used together. The longest marks in the different groups are to be recognized only in leap-year, the other marks being used for ordinary years between leap-years. It will be 85 noticed that the marks are not arranged in the same order in all of the groups G². At the beginning of January and February they are arranged in a certain order, which is changed at the beginning of March, the change continuing throughout the remaining months. This change in the position of the marks at the beginning of March or ending of February is made necessary by leap-year. By the use of the pointer H and the subdivisions G² the demonstrator can readily bring out the difference 90 between the ordinary years and the leap-years. Starting with the pointer H at the longest mark January 1, the beginning of leap-year, we move the carriage to the longest mark, 100 February 1. The carriage has passed over thirty-one days. Now starting at February 1, longest mark, we move the carriage to March 1, longest mark, and find this has taken twenty-nine days, for it is leap-year. This 105 "leap" has made it necessary to place the group of marks in a different position. We now move the carriage through March, thirty-one days, to April 1, longest mark, and in the same manner around to the longest mark 110 December 1. The carriage is now moved through December, thirty-one days, and it arrives at the mark in the group G² next in length to the longest mark. Now as the carriage started from the longest mark it completed the revolution around the sun (three hundred and sixty-five and one-fourth days) when it arrived at this longest mark and has now traveled three-fourths of a day more than a complete revolution, completing leap-year, 115 which has taken three hundred and sixty-six days. The mark the pointer has now reached—viz., the one next in length to the longest mark of the group—represents January 1 first year after leap-year. Now moving the carriage 120 on through January, thirty-one days, we arrive at the corresponding mark February 1. We see that February 1 is three-fourths of a day ahead of where it was leap-year and the last three-fourths of the last day 130

of January this year are in the same place that the first three-fourths of the first day of February were last year. Moving the carriage on through February (twenty-eight days only this year) we will arrive March 1 at the corresponding mark—that is, the one next in length to the longest mark and which is one-fourth of a day behind where March 1 was in leap-year. We move the carriage around in this manner (ignoring all marks in the groups G² except the one next in length to the longest mark) until it has passed through three hundred and sixty-five days, for we have only three hundred and sixty-five days in this year, and as three hundred and sixty-five days is one-fourth of a day less than a complete revolution we will reach the mark next in length to the shortest mark in the group. This mark represents the beginning of January second year after leap-year. We move the carriage from this mark on around the web, recognizing only the corresponding mark in each group as the beginning and ending of the months for this second year after leap-year, and we will find that traveling three hundred and sixty-five days the carriage has necessarily fallen back to the shortest line in the group and which is one-fourth of a day behind where we started from at the beginning of the year. This shortest line represents the beginning of January the third year after leap-year, and moving the carriage from this line on around the web for three hundred and sixty-five days the carriage will reach the longest line in the group, representing January 1 the beginning of another leap-year.

Having thus described my invention, I claim as new and desire to secure by Letters Patent—

1. A tellurian provided with a fixed elliptical guideway having a graduation indicating the twelve months of the year and days of the month and a subdivision into quarters of one day in each month, a carriage mounted to travel on the said guideway and carrying a globe, and a pointer on the carriage, indicating on the said graduation, as set forth.
2. A tellurian comprising a fixed elliptical guideway representing the yearly orbit of the

earth, a carriage mounted to travel on the said guideway, a gravity-support comprising a shaft extending transversely and journaled on the said carriage, the said shaft being provided at one end with a weight, an angular arm at the other end of the shaft, and a curved arm extending from the last-mentioned end of the shaft, and a globe journaled in bearings in the said arms and having its axis standing at an angle to the axis of the said guideway, as set forth.

3. A tellurian comprising a fixed elliptical guideway representing the yearly orbit of the earth, a carriage mounted to travel on the said guideway, a gravity-support extending transversely and journaled on the said carriage, a globe journaled in the said support and having its axis standing at an angle to the axis of the said guideway, and a friction device on the said carriage, engaging the said guideway, for holding the carriage at any point on the guideway, as set forth.

4. A tellurian, comprising a supporting-frame, a fixed elliptical guideway on said frame, the said guideway having an inwardly-extending web provided on the front face with graduations indicating the months of the year and days of the month, and one day of each month having a subdivision representing quarter-days, a carriage mounted to travel on the said guideway, a globe carried by said carriage, and having its axis standing at an angle to the axis of the said guideway, a pointer on the carriage indicating on the said graduation, and a forwardly-projecting rod arranged in the axis of the guideway and carrying the representation of the sun, the said representation of the sun being located in a vertical plane parallel to the guideway and extending through the center of the globe, as set forth.

In testimony whereof I have signed my name to this specification in the presence of two subscribing witnesses.

CHARLES FREDERICK BLAKESLEE.
